**LIQUID CONCENTRATE AND WATER MIXING
AND DISPENSING SPRAY GUN**

Anthony Carsello, Rolling Hills, Calif., assignor to
Dream Flo Systems, Inc., Torrance, Calif.

Filed Mar. 2, 1972, Ser. No. 331,448

Term of patent 14 years

Int. Cl. D23—01

U.S. Cl. D23—18

FIG. 1.

FIG. 2.

FIG. 3.

FIG. 4.

FIG. 5.

FIG. 1 is a front view of a liquid concentrate and water mixing and dispensing spray gun showing my new design;

FIG. 2 is a side view;

FIG. 3 is a rear view;

FIG. 4 is a top view; and

FIG. 5 is a bottom view.

The broken line showing of a fitting suitable for attaching to a garden water hose in FIGS. 1, 2 and 3 is for purposes of illustration only.

I claim:

The ornamental design for a liquid concentrate and

water mixing and dispensing spray gun, as shown and described.
